GRINDING MACHINE

Ralph E. Price, Harold E. Balsiger, and Milburn A. Hollengreen, Waynesboro, Pa., assignors to Landis Tool Company, Waynesboro, Pa.

Application February 28, 1940, Serial No. 321,310

16 Claims. (Cl. 51—95)

Our invention relates to grinding machines, particularly of the type known as plain cylindrical grinders, although many of the features hereinafter described are applicable to other types of grinding machines.

It is an object of our invention to provide a machine wherein all the controls are within easy reach of the operator.

A further object is to provide a single control member with multiple functions.

A further object is to provide means to compensate for variation in temperature of the fluid in a hydraulic system whereby to obtain uniform functioning under all temperature conditions.

A further object is to provide an improved coolant system.

A further object is to provide an interlocking relation between the wheel feed mechanism and the work drive motor.

A further object is to provide an improved feed mechanism.

Figure 1 is a front elevation of our machine.

Figure 2 is a sectional right hand end elevation of the wheel support and feed mechanism.

Figure 3 is a sectional front elevation of the wheel support and feed mechanism.

Figure 4 is a sectional elevation on line 4—4 of Figure 3.

Figure 5 is a sectional elevation of the rapid feed reversing valve and the viscosity compensator.

Figure 6 is a section thru the timing valve.

Figure 7 is a sectional front elevation of the main control valve.

Figures 8A, B, and C are sectional elevations of pilot valve 190 of Figure 7 in position for normal traverse, dressing and high speed traverse, respectively.

Figure 9 is a vertical section thru the traverse speed control valve.

Figure 10 is a vertical section thru the traverse plunger cut selector valve.

Figure 11 is a section on the line 11—11 of Figure 10.

Figure 12 is a section thru the tarry valve.

Figure 13 is a section thru the feed control valve.

Figure 13A is a section on the line 13A—13A of Figure 13.

Figure 14 is a section on the line 14—14 of Figure 13.

Figure 15 is a section thru the valve which determines the traverse speed for dressing.

Figure 16 is a section thru the combined hood and water nozzle.

Figure 17 is a section on the line 17—17 of Figure 16.

Figure 18 is a sectional plan view of the footstock.

5 Figure 19 is a wiring diagram.

Figure 19A is a wiring diagram of the headstock drive motor circuit.

Figure 20 is a piping diagram.

10 Numeral 10 indicates the bed of a grinding machine, 11 a work carriage slidably mounted thereon, 12 a swivel table mounted for angular adjustment on said carriage, 13 a headstock, and 14 a footstock, both mounted on said table. A work piece W is rotatably supported on headstock center 15 and footstock center 16. Any suitable driving device on the headstock serves to rotate said work piece. A water guard 17 prevents coolant from splashing on the operator. Carriage 11 may be shifted manually by means of

15 handwheel 18 thru suitable mechanism, not shown. When actuated by power the direction of movement of the carriage is controlled by a reversing lever 19 actuated by dogs 20 and 21 on dog rack 22. The rate of traverse is determined by the setting of valve 23. For dressing traverse the rate is controlled by valve 24. A wheel base

25 having a grinding wheel 26 rotatably mounted thereon is slidably mounted on the bed 10 for movement toward and from the work carriage. A cover member 27 hinged for easy inspection encloses the wheel base and grinding wheel and has a separate compartment therein for each of said parts. A handwheel 28 provides a manual means for shifting said wheel support toward

30 and from the work. A second cover 29 similar in shape and size to cover 27 encloses the space over the coolant tank.

Footstock

40 Footstock 14 comprises a spindle 52 slidably mounted therein. Said spindle has a center 16 inserted at one end and a flanged nut 53 for limiting the movement of said spindle. Said spindle may be actuated in a conventional manner by means of lever 54.

45 A plunger 55 actuated by spring 56 and bearing against a portion of said lever urges said spindle and center toward operative position. Said center may be withdrawn also by a piston 57 slidably mounted in a cylindrical bore 58 in said footstock. Said piston may be actuated in one direction by fluid under pressure from a valve 59 which is operated by a pedal 60. When so actuated, said piston 55 will engage the flanged portion of nut 53 and

shift said nut and spindle in a direction to withdraw center 16 to an inoperative position.

Feed mechanism

In Figures 2, 3, 4, 5 and 6 are shown the mechanisms both manual and power operated for moving the wheel support 25 toward and away from a work piece. There are in effect four of these mechanisms: (1) the manual mechanism actuated by handwheel 28; (2) a rapid feed mechanism; (3) a continuous grinding feed mechanism; (4) an intermittent grinding feed operated during traverse grinding and consisting of a mechanism for actuating the above mentioned continuous feed mechanism intermittently.

The manual means for feeding wheel 25 includes a handwheel 28. Said handwheel is connected thru a system of gears to a shaft 40. Said handwheel is rotatably mounted on a bushing 62 on shaft 40. A ring gear 63 is mounted on a flanged portion of handwheel 28. Said ring gear fits on said handwheel tightly enough to rotate therewith unless held against rotation by some means such as locking pin 68. A second ring gear 64 is keyed to shaft 40. A differential gear consisting of two pinions 65 and 66 is rotatably mounted in a recess in said handwheel. Said gear is supported on a shaft 67 in said handwheel and parallel to the axis thereof. Pinion 65 meshes with ring gear 63 and pinion 66 with ring gear 64. When handwheel 28 is turned with locking pin 68 in back position as shown, the drive from handwheel 28 to shaft 40 is direct, with said handwheel, ring gear 63, differential pinions 65 and 66, ring gear 64, and shaft 40 turning as a unit. When ring gear 63 is locked by pin 68, the drive from handwheel 28 to shaft 40 is a 10 to 1 ratio. As the handwheel 28 and differential pinions 65 and 66 rotate about the handwheel axis, said pinions are caused to rotate about their own axis by the engagement of pinion 65 with ring gear 63. Pinion 66 thus causes rotation of ring gear 64 and shaft 40 at the rate of one revolution to ten revolutions of handwheel 28. Obviously this ratio of 10 to 1 may be varied to suit any particular case. With this fine feed arrangement in combination with the other features of the feed mechanism to be described later, the operator may accurately and easily effect any change in size directly by setting the hand feed and without measuring a work piece after each of a series of test cuts.

On one end of shaft 40 is a cut a worm (not shown). Said worm engages a worm gear 42 which is secured to a vertical shaft 43. Both of said shafts are supported in bearings in the wheel support 25. Said handwheel shaft is mounted on three ball bearings, one of which supports the worm end thereof. On an extension of said shaft beyond the worm portion a finger 35 is rotatably mounted in frictional engagement therewith. Said finger engages a switch 37 for controlling headstock motor 490. At the lower end of said shaft 43 is secured another worm gear 44. Said worm gear engages a worm or feed screw shaft 45 rotatably and slidably supported in the bed 10. Said screw may be moved rapidly endwise by piston 46 in cylinder 47, or it may be rotated by rack 50 in contact with pinion 51 on said screw shaft, or it may remain stationary while worm gear 44 turned by hand-wheel 28 moves relative thereto carrying with it the wheel support 25. In either of the first two cases the worm gear 44 becomes in effect a nut because it is held against rotation by worm gear 42 and the

worm on shaft 40. During the rapid feed, the screw shaft 45, worm gear 44, and wheel support 25, are moved bodily. The backlash between screw 45 and worm gear 44, between worm gear 42 and its worm and the torsional strain in shaft 43 are taken up during the rapid feed movement. When screw shaft 45 is rotated by piston 70 for a grinding feed, gear 44 and wheel support 25 are moved relative thereto while said screw remains motionless axially. The backlash mechanism described above may be taken up either in response to rotation of screw 45 or to rotation of handwheel 28. At the end of the grinding feed, the feeding movement stops and grinding stops as soon as the wheel sparks out. Piston 46 is adjustably mounted on the threaded end 48 of shaft 45 and is prevented from turning thereon by a split nut 49 which has a clamping screw 69 extending beyond said nut into an opening 61 in piston 46. In order to eliminate backlash in the feed mechanism, a lock mechanism is provided to prevent rotation of shaft 43 during the movement of the wheel support by power. While the design of the feed mechanism does not require a backlash mechanism this one is set forth as an optional construction. Said mechanism consists of a pair of tubular members 30 and 31 slidably mounted in a bore 32 in wheel base 25 adjacent vertical shaft 33 so that said bore joins the bore thru which said shaft passes. Said tubular members are axially spaced in bore 32 and a portion of the inner end surface of each is shaped to conform to the cylindrical surface of shaft 43. A reduced portion 33 of a shaft 34 passes thru said tubular members. The end of said portion is threaded to fit the threaded bore of member 30. Shaft 34 extends beyond the wheel base at the left hand side thereof and has mounted thereon a handle 35. Turning said handle results in drawing said tubular members together to lock shaft 43 against rotation or in separating said members to release said shaft.

In addition to rack 50 and pinion 51 the grinding feed mechanism includes a piston 70 integral with said rack. Said piston is mounted for axial movement in cylinder 71. The extent of movement of piston 70, and hence the amount of grinding feed, is determined by the setting of an adjustable positive stop 73 in the head of cylinder 71. The amount of adjustment of said stop may be determined by a knob 75 graduated in terms of wheel movement. A threaded insert 74 in stop 73 enables the operator to set knob 75 accurately. For example, with piston 70 at the extreme left hand position and knob 75 set at zero, insert 74 may be adjusted until it engages the head of piston 70. In this position there would be no grinding feed because piston 70 could not be returned to a position from which it could rotate screw shaft 45 to effect such a feed.

The means for supplying fluid under pressure to cylinder 47 consists of a valve 80 in a housing 81, said housing is enclosed at both ends by end plates 82 and 83. Fluid under pressure directed by valve 262 thru line 421 may be applied at the right hand end of said valve 80 to shift same to direct other fluid under pressure thru lines 84 and 85 to the head end of cylinder 47. Exhaust pressure or a spring 76 may be applied at the opposite end of said valve. Fluid connections from valve 80 to cylinder 47 include two axially spaced lines to each end thereof. Lines 84 and 85 lead to the head end of cylinder 47 and lines

86 and 87 lead to the rod end thereof. Check valves 88 and 89 permit the passage of fluid under pressure to cylinder 41 thru lines 85 and 87 but the exhaust fluid returning thru said lines must pass thru throttle valves 90 and 91, respectively. Lines 84 and 86, and their corresponding ports in cylinder 41, are located between lines 85 and 87. A piston 46 moves from one end of its stroke to another, the first part of the stroke is open to unrestricted exhaust thru one of the lines 84 or 86, but as the piston 46 continues it cuts off this exhaust line and thereafter the only exhaust is thru lines 85 or 87 depending on the direction of movement, and the throttle valve in each of these lines restricts the flow of exhaust fluid and thus cushions the stopping of the wheel support.

A line 473 from the head end of cylinder 71 to the left hand end of valve housing 81 permits expulsion of air in said cylinder, thus eliminating the need for bleeder tubes. Bleeder tubes are a disadvantage at slow speeds because the volume of fluid supplied at such speeds does not exceed the capacity of the bleeder sufficiently to maintain the necessary minimum pressure on the rapid feed piston to keep it moving. With our improved arrangement, valve 80 closes off line 473 during feeding so that full pressure is exerted against piston 70.

Timing mechanism

In Figure 6 is disclosed a timing valve for determining the duration of a plunge cut grinding operation. Said valve consists in the valve member 100 slidably mounted in a bore 101 in cylindrical housing 102, sometimes referred to hereafter as a timer. One end 103 of said valve is smaller in diameter than the rest of the valve and fits in a bore 104 of corresponding diameter formed in a member 105 inserted in bore 101. The portion of said valve which may be acted on by fluid under pressure in lines 114 and 115 is therefore smaller than the opposite end thereof. An end plate 106 has a line 107 therein leading to bore 104. Another end plate 108 has a line 109 therein leading to bore 101. On one side of housing 102 are two lines 110 and 111 located toward the right hand end of the valve. In the position of valve 100 shown, line 111 is connected thru peripheral groove 112 of valve 100 with a line 113 on the opposite side of said housing. On said opposite side but toward the left end of the valve are two additional lines 114 and 115. Said lines are connected by a passage 116 in which is located a ball check valve which permits passage of fluid from lines 114 and 115. Valve 100 has a closed bore forming a passage 117 which is connected to the chamber at the left end of bore 101 thru a port 118. Spaced axially from said port is a second port 119 joining said bore 101 and passage 117 thru a peripheral groove 123. Said groove forms a chamber between said valve and said bore 101. Movement of valve 100 to the left is retarded by the fluid exhausting from the bore 101 thru line 115 and thru a throttle valve 121 in said line. When the valve moves to a point where port 119 coincides with line 114, the fluid may be released thru passage 117, passage 116, port 118 in the valve, and exhaust line 114 in the housing, thus permitting the valve to move quickly to reverse position.

Relief valve

In Figure 5 is shown another novel feature of our hydraulic system. This feature is a relief

valve which compensates for variation in viscosity so that mechanisms operated by fluid under pressure will function at the same rate regardless of the temperature of the hydraulic medium. 5 Said valve consists of a movable valve member 130 having opposite ends of different diameter, and mounted in a cylinder bore 131 having an internal surface corresponding in shape to said valve member. Said valve member is hollow 10 from end to end and contains a check valve 140 which will permit the passage of fluid from the small end to the large end under certain abnormal conditions. Said valve is connected into the hydraulic system at a point relatively close to the pump 132. The small end 133 of cylinder 131 may be connected directly to the pressure supply line 137 leading from pump 132. The large end 134 of said cylinder may be connected to said supply line thru line 135. A throttle 20 valve 138 for regulating the pressure in the system is placed in line 137 between the points of connection between said supply line and said cylinder. The small end 133 of cylinder 131 is subjected to pressure which is determined by the 25 setting of valve 138. The pressure at the large end 134 of said cylinder is determined by the resistance to flow offered by the mechanism or mechanisms to be actuated by the fluid under pressure. As the pressure in the large end of the cylinder approaches that in the small end, said valve member 130, because of the difference in diameter, will be shifted toward the small end to a position to open exhaust line 139 and relieve any excess pressure in the system.

Traverse mechanism

The traverse mechanism on our machine consists of a cylinder 150 secured to bed 10, and a piston 151 slidably mounted in said cylinder with 40 a piston rod 152 protruding from one end and a tail rod 153 protruding from the other end, both of said rods are attached to carriage 11 by means of suitable brackets 154 and 155. The supply of fluid under pressure for driving said piston is 45 controlled by a series of valves mounted in a body 160. Said valves include a start and stop or bypass valve 161 slidably mounted in bore 162. Said valve may be actuated to operative position, in this case the left hand position, by fluid under 50 pressure from a source to be described later, and in the opposite direction by a spring 163. Cylinder 150 is connected to said valve thru lines 165 and 166. Fluid under pressure for actuating piston 151 is supplied to valve 161 from a pressure 55 actuated reversing valve 170 thru lines 171 and 172. Valve 170 is mounted in a bore 173 in the valve body 160 and has reduced portions 174 and 175 at opposite ends thereof. Said reduced portions fit in tubular inserts 176 and 177 at opposite ends of bore 173. Each end of said valve is 60 bored to form connecting passages 178 and 179, connecting spaced radial passages 180 and 181 at one end, and 182 and 183 at the other end. In one extreme position of said reversing valve 170, 65 radial passages 180 and 182 are aligned with exhaust ports 185 leading into exhaust passage 186, and in the other extreme position radial passages 181 and 183 are aligned with said exhaust ports.

70 Actuating fluid under pressure is supplied to said reversing valve from a pilot valve 190 thru a line 191. Said pilot valve also directs fluid under pressure alternately thru lines 192 and 193 to shift reversing valve 170 in one direction or the other. Opposite ends of bore 173 are con-

ected thru lines 194 and 195 in which is located a tarry valve 291.

Fluid under pressure in lines 192 and 193 is also directed to actuate an automatic feed valve 200 in bore 201. The ends of valve 200 are identical in structure with those of valve 170 and include reduced end portions 202 and 203, radial passages 204 and 205, 206 and 207, connected by axial passages 208 and 209 respectively. Said end portions 202 and 203 are fitted in tubular inserts 210 and 211. Lines 212 and 213 connect opposite ends of bore 201. A throttle valve 214 determines the rate of flow of fluid in said lines and therefore the rate of movement of valve 200. Said valve receives a supply of fluid under pressure from feed control valve 308 thru line 221. Said fluid is directed by valve 308 thru either of the lines 222 or 223 depending on the direction of movement of said valve. Said lines join into a single line 224 leading to valve 161. The volume of fluid directed thru said lines depends on the rate of movement of valve 200.

Pilot valve

The pilot valve 190 is mounted in a bore 375 in valve body 160. Said valve has two longitudinal passages therein; a long one 376, and a short one 377. Three spaced, radial ports 378, 379 and 380 in valve 190 are joined by passage 376. Three other spaced, radial ports 381, 382 and 383 in said valve are joined by passage 377. The function of passage 376 and associated ports is to provide escape for exhaust fluid in various positions of valve 190. The function of passage 377 and associated ports is to provide a continuous supply of fluid under pressure to hold valve 161 in operative position while valve 190 is reciprocated during a traverse grinding operation. Said valve 190 has three different strokes, a short stroke for normal traverse determined by pin 231 in panel 230, a longer stroke determined by springs 233 and 234 for dressing, and a still longer stroke for high speed traverse.

The control members for the hydraulic system are mounted in the bed 10 with knobs or handles for same protruding thru a cover panel 230. In some cases the movable part of a control member is secured to said panel while the stationary part is solidly mounted in the bed 10.

In Figure 9 is shown the reversing and traverse control member. This member consists of a stationary tubular part 235 held securely in the bed 10 by means of a screw 236. A core member 237 is rotatably mounted in said tubular part 235 and extends thru said panel 230. A flanged portion 238 at one end of said member bears against a faced off portion of said panel and is held in that position by a collar 239 on said core inside said panel. Said collar is secured to said core by means of a screw 240. Pivotaly attached to said flanged member is the lever 19. Said lever is bored to receive a spring pressed plunger 242 which bears against a cam surface 243 on flange 238 to hold said lever in position so that a lug 244 thereon will be in the path of dogs 20 and 21. A pin 231 on said panel extends into an elongated recess 232 in lever 19 to limit the movement thereof during normal traverse. When it is desired to permit carriage movement beyond the limits set by said dogs, said lever may be pulled back against the action of said spring pressed plunger 242 in which position the lug 244 will be out of the path of said dogs. In this position also pin 231 will have no effect on lever 19. However, leaf springs 233 and 234 secured to the end

5 plates of valve 160 and extending into the path of valve 190 mark the limit of movement of said valve during a dressing operation. For a rapid traverse movement said valve is shifted still farther against the springs 233 and 234. At the end 10 of said core member 237 inside the bed is mounted an arm 245 which extends downwardly to engage pilot valve 190. Said core member 237 is bored to receive a throttle valve 246 which controls the 15 flow of fluid between spaced radial passages 247 and 248. Said throttle valve may be adjusted by a knob 249 which is threaded into core 237. Passage 247 is aligned with an exhaust passage 250 in the tubular part 235. A check valve 251 in said passage maintains a slight back pressure on the exhaust system. Passage 248 is aligned with an inlet passage 252 which in turn is connected to the exhaust port of pilot valve 190. Said valve is grooved circumferentially at each of said radial 20 passages so that fluid may pass thru said core regardless of its angular position.

Traverse and plunge cut selector

Figure 10 discloses a valve the function of which is to prevent traverse movement of the work carriage during a plunge cut grinding operation. Said valve consists of a stationary tubular member 260 inserted in the bed 10 and held in place by a screw 261. A valve member 262 is rotatably mounted in panel 230 for insertion in said tubular member. Said valve is held in proper axial position by a flanged portion 263 thereon which bears against a pad 264 on panel 230. Said pad is faced on both sides. The flange bears against the outside while a collar 265 held in place by a screw 266 bears against the inside of said pad. A knob 267 on said valve provides means for shifting said valve from one position to another. Member 260 has two radial passages 268 and 269 in the upper portion thereof. Said passages are connected by a short passage 270. Fluid under pressure may be introduced thru port 271. The lower portion of member 260 has two spaced radial passages 268' and 269' which are in effect continuations of passages 268 and 269. Fluid under pressure is conducted from passage 268' thru port 272 to actuate valve 80. Another radial passage 273 in member 260 in the same plane as passages 268 and 269' join a longitudinal passage 274 therein which directs fluid under pressure to the traverse mechanism. A longitudinal passage 275 joining radial passage 269' directs fluid back to the reservoir. Valve 262 has two spaced peripheral grooves 276 and 277 in alignment with passages 268 and 269. Groove 276 is continuous and permits passage of fluid as long as fluid enters port 271. Groove 277 is broken by a plug 278 which prevents passage of fluid in some angular positions, for instance, in the position shown in Figure 11. In this position the pressure of the fluid in passage 269 exerts such a force that it binds valve member 262 and prevents or makes difficult the turning of said valve while the fluid is directed thru passage 268 to move the wheel to and hold it in grinding position.

Tarry

The tarry valve is disclosed in Figure 12, and is of the same general construction as previously described valves in that it consists of a stationary tubular member 196 inserted in the bed 10 and held in place by means of a screw 230. A longitudinal passage 281 in member 196 joins a radial passage 282, and another longitudinal passage 283 joins a radial passage 284. A core member 285 has

a pair of spaced peripheral grooves 286 and 287 in each of which are radial passages 288 and 289 respectively. Passages 288 and 289 are joined by a longitudinal passage 290 in which is inserted a tarry valve 291. Fluid from the reversing valve bore 173 passes thru lines 194 and 195 and said valve in both directions. Said core is threaded into tubular member 196 and is therefore not rotatable as in some of the other valves. Valve 291 may be adjusted axially by means of a knob 292 which is threaded for this purpose in core 286.

Feed control valve

In Figure 13 is disclosed the valve for controlling the feed mechanism and which is effective also to start the grinding operation. Said valve like previously described valves consists of a short tubular member 220 inserted in the bed 10 and secured therein by means of a screw 301. In the upper part of said member 220 is a longitudinal passage 302 joining a radial passage 303. In the lower part of member 220 are a pair of spaced radial passages 304 and 305. A longitudinal port 306 connects with passage 304, and a longitudinal exhaust passage 307 connects with passage 305. Groove 310 in valve 308 is not continuous by reason of a pin 332 therein. The angular position of said pin and hence that of valve 308 determines whether fluid shall be directed to the traverse selector valve 262 or to the exhaust passages 305 and 307. Valve 308 has spaced peripheral grooves 309 and 310 in alignment with the radial passages in tubular member 220. A radial passage 311 in groove 310 extends part way thru said valve 308. A radial passage 312 in groove 309 extends all the way thru said valve and at right angles to the passage in groove 310. A longitudinal passage 313 connects said radial passages. A throttle valve 314 may be adjusted by means of a knob 315 threaded in said valve 308 to regulate the flow of fluid between said radial passages 310 and 312. Said fluid passes from passage 312 thru port 306 and line 221 to feed cylinder 70. Valve 308 has a flanged end 320 which bears against a pad 321 on panel 230. Said pad is faced on both sides. A collar 322 held in place on said valve by a set screw 323 bears against the other side of said pad. A lever 324 for rotating said valve 308 is formed integral with said flange. Another radial passage 330 is formed in said tubular member in the same plane as passages 303 and 305 and at right angles thereto. Said passage 330 joins a longitudinal passage 331 which directs fluid thru line 420 to the traverse plunge cut selector valve 262.

Dresser control valve

Figure 15 discloses a valve for controlling the traverse speed during a dressing operation. This valve consists of a stationary tubular member 340 held in position in bed 10 by means of a screw 341. In the upper part of member 340 is a longitudinal passage 342 joining a radial passage 343. In the lower part of said member is a longitudinal passage 344 joining a radial passage 345. A check valve 346 in said radial passage 345 permits a flow of fluid to passage 344 which is an exhaust passage. A valve 347 threaded into member 340 has two spaced peripheral grooves 348 and 349 thru which are drilled radial passages 350 and 351 respectively. A longitudinal passage 352 joins said radial passages 350 and 351. A throttle valve 353 in passage 352 may be adjusted axially by means of a knob 354 threaded into said valve 347.

Coolant system

The coolant system may consist of any suitable coolant pump driven by a motor 360. Coolant fluid from said pump may be introduced in any suitable manner into a passage 361 in cover 27. The front end of the wheel guard portion of said cover is recessed to receive a combination hood and nozzle 362 which is pivotally secured therein by a pin 363. The portion of said pin passing thru said hood has a flat surface 364. The hole in said hood thru which said pin passes opens at one side to a nozzle formed by the upper wall of said hood and a web portion 365. Pin 363 thus serves as a shut-off valve. A screw 366 passes thru the side of said hood and thru a slot 367 in cover 27. Said slot permits said hood to be adjusted to correspond to the size of the wheel.

Operation

Starting the machine is effected by start switch 400 which completes a circuit from L1 thru stop switch 401 to relay 1 and L3. Energizing relay 1 starts the wheel motor 402, the hydraulic pump motor 403, and generator motor 404. Another contact 405 on said relay provides a holding circuit around switch 400.

To place a work piece in the machine the operator depresses pedal 60 to shift valve 59 and direct fluid under pressure to withdraw footstock center 16. Fluid under pressure is supplied to said valve from control valve 308 when lever 324 thereof is in inoperative position. When said lever is in operative position, the line 225 is opened to exhaust thru valve 308. This provides a safety feature in that fluid under pressure cannot be supplied to withdraw said footstock center to release the work while the other parts are operating.

The operator then moves lever 324 to the right to shift valve 308 in tubular member 220, releasing the pressure in line 225 and permitting a flow of fluid under pressure from line 137 thru passage 302 in groove 310, and passages 330 and 331 and line 420 to selector valve 262 and thru line 421 to feed timer valve 102 and rapid feed control valve 80. Said fluid is also directed by passage 311, thru throttle valve 314 passages 312 and 304 to port 306, from which it passes thru line 221

to actuate the grinding feed either continuously or intermittently, all of which will be described later.

Fluid under pressure directed by valve 262 thru line 421 passes first thru a hydraulic timer 102.

Part of said fluid passes from line 421 thru line 109 to shift the valve member 100 from right to left. Another part of said fluid passes from said line 421 thru line 111 and peripheral groove 112 of valve 100 thru line 113 to shift feed valve 80 to operative position and hold it therefor a predetermined time. Movement of valve 100 from right to left is controlled by the fluid being forced out thru line 115 and thru throttle valve 121 into line 114.

When valve 100 opens line 114 thru peripheral groove 120, passage 117, and ports 118 and 119 to bore 101 further movement is uncontrolled. Line 111 is blocked by valve 100 and line 113 is connected by peripheral groove 112 of valve 100 to line 110 which allows valve 80 by spring 76 to be returned to its original position. Valve 100 may be reset by fluid under pressure in line 114 thru valve 122 and line 115 to the left end of housing 102 when the pressure at the other end of said cylinder is released by shifting lever

324 to the left and connecting lines 420 and 421 to an exhaust passage.

When feed valve 80 is shifted from right to left by the mechanism described above, fluid under pressure from supply line 137 passes thru line 480 to said valve which directs it to line 84 and thru check valve 88 therein and line 85 to the head end of rapid feed cylinder 47. Said fluid also actuates a pressure switch 485 to start the work drive motor 490 completing a circuit thru limit switch 37 selector switch 495 to contactor 3. At the same time, contactor 2 is energized to start coolant motor 369. Said contactor has two normally open circuits and a closed circuit. The work drive motor is of the type disclosed in copending application, Serial No. 238,657, filed November 3, 1938, and includes the motor 490, a generator 491 for supplying current to said motor, a rheostat 492 for varying the voltage on the generator field and an exciter 493 for said generator. One of said normally open circuits is in the line between the exciter and the generator, the other between the generator and the motor. The normally closed circuit is in the motor armature circuit and provides a dynamic brake for motor 490 when contactor 3 is deenergized. The motor circuit does not form a part of the present invention except for the method of starting, and will be further referred to only insofar as the starting device is concerned. Piston 46 in cylinder 47 and wheel support 25 are moved rapidly to position the grinding wheel 26 close to the surface of the piece to be ground. Fluid is discharged from cylinder 47 thru lines 86 and 87. Line 86 is unrestricted so that piston 46 moves at top speed. After piston 46 has closed line 86 said fluid can exhaust only thru line 87, and throttle valve 91 therein checks the speed of piston 46 and provides a cushioned movement against a positive stop. After passing thru valve 91 exhaust fluid enters line 86 from which it passes thru valve 80 to exhaust passage 139b. On the withdrawal movement, throttle valve 90 in line 85 effects the cushioning. The rapid feed movement is limited by screw 45 engaging a stop 77.

Assuming that the grinding operation is a plunge cut, fluid under pressure in line 221 enters chamber 455 of valve 161 and is directed thru passage 410, valve 470, and line 472 to the head end of cylinder 71. Piston 70 in said cylinder moves rack 50 in mesh with pinion 51 on feed screw 45. Said screw rotates in mesh with worm gear 44 on the end of vertical shaft 43. Said gear 44 and gear 44 are held against rotation by worm gear 42 at the other end of the shaft in mesh with a worm (not shown) on shaft 40 of handwheel 28. Thus gear 44 and with it the entire wheel support assembly must move relative to screw 45 in response to rotation thereof. When valve 80 is shifted from left to right as previously described in connection with the operation of the rapid feed, fluid under pressure in line 86 which effects withdrawal of the rapid feed mechanism also enters the rod end of cylinder 71 to reset piston 70 and the grinding feed mechanism. This reset is always a continuous movement and is independent of the work traverse movement. Valve 80 also opens an additional exhaust from the head end of cylinder 71 thru lines 472 and 473 thru said valve

80 to exhaust lines 139a and 139 thus permitting a quick reset of the grinding feed mechanism. Line 473 also serves as a bleeder line to permit the escape of air from cylinder 71. This line is blocked by valve 80 during the feed movement.

In order to control the amount of stock removed during a grinding cycle, the stroke length of piston 70 and hence of the grinding feed may be adjustably limited by stop screw 73. The exact amount may be set by graduated knob 75.

To reset the feed mechanism for a change in size the operator uses the graduations on the handwheel 28 by which he makes a direct setting from one size to another. For example, if it is desired to increase or decrease a given size by .010" the change will be counted out on the graduations and the position of the wheel surface will be shifted .010". Thereafter, for each grinding operation the wheel will move in to the same position and once it has sparked out, it will grind no further.

Lost motion in the feed mechanism exists between worm gear 44 and screw 45, between worm gear 42 and its worm (not shown) and the torsional strain in vertical shaft 43. This lost motion is the same for every feed movement and turning handwheel 28 merely changes the position of the grinding wheel at which the lost motion is all taken up. This is true regardless of the direction of movement of the handwheel or the position of the wheel base. This lost motion is all taken up during the rapid feed movement before the grinding feed begins. Any adjustment of the feed by handwheel 28 takes said lost motion into account and the change in size is that indicated by the movement of the handwheel. The rapid feed movement ends when screw 45 engages a positive stop 77 so that when said screw is rotated for a grinding feed it cannot move axially relative to worm gear 44 before said gear begins to move carrying the wheel support with it. Since all lost motion is taken up said gear cannot rotate in response to rotation of said screw. Therefore, it becomes in effect a nut and moves bodily along with the wheel base and grinding wheel relative to screw 45.

If the work to be ground requires a traverse movement, knob 267 will be turned so as to direct fluid from passage 269 thru passages 273 and 274 (see Figure 11) line 425 chamber 426 in valve 190 and thru line 427 to valve 161 to shift said valve to the left. With said valve 161 in this position line 166 leading to one end of cylinder 150 is connected thru chamber 430 of valve 161 with line 172. Line 165 leading to the other end of cylinder 150 will be connected thru chamber 432 of valve 161 with line 171. Fluid under pressure for shifting piston 151 in cylinder 150 and hence for traversing carriage 11 is conducted from pressure line 137 thru line 435 to chamber 436 in valve 190. Said chamber is in constant connection with line 191 leading to reversing valve 170. However, as said valve is actuated either by hand or by dogs 20 or 21 on carriage 11, said chamber and the fluid supply passing therethru are connected alternately with lines 192 and 193. Fluid under pressure in said lines is directed alternately to opposite ends of valves 170 and 200 to effect reciprocating movements thereof. When said fluid acts on the small portion 174 of valve 170, said valve moves rapidly to the right until it covers the port leading to exhaust line 186. The fluid which is thus trapped between the end of the valve and insert 176 must pass thru line 195, tarry valve 291, and line 184

to the corresponding chamber at the other end of the valve. The setting of valve 291 determines the rate of flow and hence the speed of movement of the valve during this period. The slower the valve travels the longer the dwell period.

As said valve covers the port leading to exhaust line 186, the land portion 440 of valve 170 covers line 191 and at the same time the end portions of the valve cover the ports leading to exhaust line 186. In this way the traverse movement of the carriage is stopped positively and accurately. Said valve continues to move toward the right at a rate determined by the setting of valve 291 until the radial passages therein come in line with the port leading to exhaust line 186. The entrapped fluid may then escape thru radial passages 180, axial passage 178 and passage 181 to exhaust line 186, thus permitting valve 170 to move rapidly to reverse position. Valve 170 has thus been shifted to a position where fluid under pressure from line 191 is directed by said valve thru line 171 and chamber 432 of valve 161 to line 165 leading to the right hand end of cylinder 150, thus causing piston 151 and carriage 11 to move to the left. Exhaust fluid from the other end of the cylinder is carried thru line 166, chamber 430 of valve 161 and line 172 to valve 170 where it is directed into exhaust line 445. Said line is divided into two branches 446 and 447. Line 446 leads to the dresser control valve 347 shown in Figure 15. Line 447 leads to a chamber 448 in valve 190 and from there thru a line 252 and thru the throttle valve portion 246 of core 237. The rate of traverse is determined by the setting of said throttle valve 246 which is adjusted manually by means of knob 249. The normal stroke of valve 190 is so short that chamber 448 is always in position to direct fluid from line 447 to line 252. When selector knob 267 of valve 262 is shifted to change from the plunge cut to the traverse cycle, pressure on valve 161 is relieved and said valve is shifted by spring 163 to the right to connect lines 221 and 410. Fluid is thus directed thru valve 470 and line 472 to cylinder 71 to effect a continuous movement of feed piston 70.

At the same time the reversing valve 170 is shifted, fluid under pressure is directed thru the same line 192 to shift automatic feed valve 200. Said fluid acts on a reduced portion 203 of said feed valve in the bore of tubular insert 211. The fluid trapped between the one end of said feed valve and the insert is discharged thru a line 212 to the corresponding space at the opposite end of said valve. A throttle valve 214 in said lines 212 and 213 determines the rate of flow of fluid and hence the rate of movement of said valve 200. Said throttle valve as a rule need be adjusted only when the set-up of the machine is changed. Fluid under pressure is supplied to said valve 200 from valve 308 thru lines 221 and 450. Throttle valve 314 which is a part of valve 308 determines the volume of fluid passing thru valve 200. Said feed valve moves rapidly to a position to connect line 450 with line 223. Fluid then passes thru line 224 chamber 455 in valve 161 and line 410 to feed cylinder 71. Said flow continues as long as lines 450 and 223 are in communication. This period is determined by the rate of movement of the valve which is in turn determined by the setting of valve 214. At the end of this period the entrapped fluid in the space at the end of the valve is released thru passages 204, 205 and 208 in said valve, said passage 205 having connected with exhaust line 456. Valve 200

75

thereupon moves rapidly to the end of its stroke. The fluid which passes thru said valve during the open portion of the stroke causes an incremental movement of the slow feed piston 70. The magnitude of each increment is determined by the length of time during which fluid passes thru said valve, and the velocity of the fluid. The velocity is determined by the setting of valve 314 (Figure 13). Thus at each reversal of the carriage an automatic feed valve is actuated simultaneously with the reversing valve to effect a feeding movement of the grinding wheel toward the work.

In the operation of valve 190 there are three different ranges of movement; a short movement for normal traverse, a longer movement for dressing, and a still longer movement for rapid traverse. Figures 8A, B, and C shows said valve in the left hand position for each range of movement; A, normal; B, dressing; and C, rapid traverse.

During normal traverse, as illustrated in Figure 8A, valve 190 has a very short movement which is limited by pin 231 in recess 232. Fluid under pressure from line 435 is directed alternately thru chamber 436 to lines 192 and 193 to shift the reversing valve 170 and the automatic feed valve 200. At the same time fluid from line 425 and selector valve 262 passes thru chamber 426 in valve 190 and then thru line 427 to actuate bypass valve 161 and position it for traverse operation. Exhaust fluid from cylinder 150 is directed by valve 170 into line 445 from which it passes thru line 446 to dressing control valve 347 and thru line 447 and chamber 448 of valve 190 and line 252 to traverse control valve 246. The minimum traverse speed is obtained with dresser valve 347 closed entirely and with valve 246 at its smallest opening. The maximum traverse speed is obtained with both valves wide open.

During dressing traverse lever 19 is shifted toward the operator so as to remove pin 231 to clear dogs 20 and 21. The stroke of the valve is increased as shown in Figure 8B, but is limited by the springs 233 and 234. Exhaust fluid may not escape thru line 447 and valve 246 because chamber 448 in said valve is out of alignment with the ports for lines 447 and 252. Exhaust fluid, therefore, must pass out thru line 446 and valve 347 in which a throttle valve is set to permit a carriage traverse speed suitable for dressing a grinding wheel. In this position of valve 190, chamber 426 has moved out of line with the ports to lines 425 and 427 so that fluid cannot pass from one of said lines to the other. However, fluid under pressure from line 435 may pass thru chamber 436 and port 381 to passage 377 from which it may pass thru either of the ports 382 or 383 to line 427 to hold valve 161 in operative position depending upon whether valve 190 is in its left or right hand position.

In the position of valve 190 shown in Figure 8C, said valve has been moved far enough to distort springs 233 or 234. Merely releasing lever 19 will permit said springs to return said valve to dressing speed position. Ports 382 and 383 remain in register with the port leading to line 427. The chamber 436 which directs fluid under pressure from line 435 to either of lines 192 or 193 to actuate the reversing and feed valves 170 and 200 respectively is shown out of register with fluid supply line 435. However, said chamber and said lines are in register long enough, as the valve moves from one position to the other, to permit

the passage of fluid under pressure to actuate valves 179 and 200. Exhaust fluid in line 447 may escape thru chamber 469, port 378, passage 376, port 379, and chamber 461 to exhaust line 186. In the opposite position of valve 199 said exhaust may pass directly from line 447 to chamber 461 and exhaust line 186. Exhaust thru these lines is unrestricted so that the carriage will move at maximum speed.

In order to have a continuous or plunge cut feed and at the same time a short reciprocating movement of the carriage, a bypass valve 470 is so positioned that it may direct fluid under pressure to the cylinder 71 either from valve 161 or from line 221 thru bypass passage 471.

If it is desired to cut out the traverse movement, valve 262 is turned to plunge cut position as shown in Figure 19. The supply of fluid to passages 273 and 274 is cut off and hence no fluid under pressure is directed thru line 425, chamber 426, and line 427 to shift valve 161 to a position to permit fluid under pressure from reversing valve 179 to be directed to carriage traverse cylinder and the traverse mechanism remains inoperative.

The output of the pump passes through line 137 and throttle valve 138. Said throttle valve is set to create a back pressure suitable for machine operation, and is imposed upon the smaller area of valve 130. In chamber X the pressure caused by resistance of machine operation is imposed upon the larger area of valve 130 in chamber Y. When the pressure caused by machine resistance equals the back pressure caused by the resistance of the throttle valve 138, valve 130 shifts to the right due to large area at the machine resistance end of said valve and oil escapes into exhaust line Z thus maintaining a balance of pressure on the two ends of valve 130. Since the flow through throttle valve 138 is uniform, and since the pressure on all machine elements is determined by the pressure required to force a uniform flow through valve 138 regardless of viscosity variation, the flow through any valve on the machine similar to valve 138 will be uniform.

We claim:

1. In a grinding machine, a work support, a grinding wheel support, mechanisms for effecting relative transverse and longitudinal movements between said supports, mechanism for controlling the rate and direction of said longitudinal movement including a lever having a plurality of positions in each direction of movement thereof, and means for causing a different speed for each position.

2. In a grinding machine, a wheel support, a work support, a hydraulic motor for effecting a relative longitudinal movement of said supports, speed control means for causing said longitudinal movement to take place thru a relatively high speed range, speed control means for effecting said longitudinal movement thru a relatively low speed range, a valve for determining the direction of said longitudinal movement, and means for shifting said valve thru one range to select one speed control means and thru another range to select another speed control means.

3. In a grinding machine, a work support, a grinding wheel support, mechanism for effecting relative transverse and longitudinal movements between said supports, mechanism for controlling the rate and direction of said longitudinal movement including a lever having a plurality of positions in each direction of movement

thereof, and means responsive to movement to one or another of said positions for determining the rate of said longitudinal movement.

4. In a grinding machine, a work support, a grinding wheel support, mechanisms for effecting relative transverse and longitudinal movements between said supports including a hydraulic motor, a reversing mechanism for directing fluid under pressure to one side or the other of said motor, and for directing exhaust fluid thru any one of a plurality of passages, each of said passages having means for adjusting the rate of flow therethru.

5. In a grinding machine, a work support, a grinding wheel support, mechanisms for effecting relative transverse and longitudinal movements between said supports, a selector device for rendering operative one or both of said movements, and means responsive to the fluid under pressure for causing said traversing movement for resisting operation of said selector while the wheel support is in advance position.

6. In a grinding machine, a work support, mechanism for effecting a longitudinal reciprocation of said support, a grinding wheel support, mechanism for effecting a rapid transverse positioning movement of said support, mechanism for effecting a slow transverse feeding movement of said support, means responsive to said longitudinal reciprocation for effecting said feeding movement by predetermined increments, and a bypass mechanism for bypassing said incremental feed control means whereby to provide a plunge cut feed along with said longitudinal reciprocation.

7. In a grinding machine, a work support, mechanism for effecting a longitudinal reciprocation of said support including a hydraulic motor, a reversing mechanism for controlling said longitudinal reciprocating movement, a grinding wheel support, mechanism for effecting a slow transverse feeding movement of said support, means controlled by said reversing mechanism for supplying fluid under pressure to said feeding mechanism intermittently, means for supplying a continuous flow of fluid under pressure to said feed mechanism, a valve controlled by said reversing mechanism and operable in one position to connect said hydraulic motor with said reversing mechanism and for connecting said feed mechanism with said intermittent flow of fluid, and in another position to disconnect said hydraulic motor and said reversing mechanism and to connect said feed mechanism with said continuous flow of fluid under pressure.

8. In a grinding machine, a work support, a grinding wheel support, mechanism for causing a relative longitudinal movement between said supports including a motor connected to said work support, a reversing mechanism for effecting a reciprocating movement of said motor and said work support, means for actuating said reversing mechanism, mechanism for effecting a relative transverse movement between said supports including a second motor, means operable in response to the means for actuating said reversing mechanism for causing incremental movement of said second motor, and means for varying the magnitude of said increments by varying the rate of movement of the means for causing same.

9. In a grinding machine, a work support, a grinding wheel support, mechanism for causing a relative longitudinal movement between said supports including a hydraulic motor, mech-

anism actuated by said longitudinal movement for effecting a reversal thereof including a pilot valve and a reversing valve actuated thereby, mechanism for effecting a relative transverse movement between said supports including a second motor, means for effecting incremental movement of said motor including a valve actuated by said pilot valve, and means for determining the magnitude of said increments including a throttle valve in the supply line to said pilot actuated valve.

10. In a grinding machine, a work support, a grinding wheel support, mechanism for causing a relative longitudinal movement between said supports including a hydraulic motor, mechanism actuated by said longitudinal movement for effecting a reversal thereof including a pilot valve and a reversing valve actuated thereby, mechanism for effecting a relative transverse movement between said supports including a second motor, means for effecting incremental movement of said motor including a valve actuated by said pilot valve, and means for varying the rate of movement of said valve.

11. In a grinding machine, a work support, a wheel support, mechanism for effecting relative transverse and longitudinal movement of said supports, a grinding wheel rotatably mounted on said wheel support, and a hinged cover member enclosing said support and said wheel.

12. In a grinding machine, a work support, a wheel support, mechanism for effecting relative transverse and longitudinal movement of said supports, a grinding wheel rotatably mounted on said wheel support, and a hinged cover member having two compartments one for the wheel support and one for the wheel.

13. In a grinding machine, a work support, a headstock for rotatably supporting a work piece, a motor for driving said headstock, a wheel support, means for effecting relative transverse and longitudinal movement of said supports, a coolant system including a motor driven pump, and a pressure switch actuated by the fluid under pressure for said transverse movement for starting said pump motor and said headstock motor.

14. In a grinding machine, a work support, a grinding wheel support, mechanism for causing a relative longitudinal movement between said supports including a hydraulic motor, mechanism actuated by said longitudinal movement for effecting a reversal thereof including a pilot valve and a reversing valve actuated thereby, mechanism for effecting a relative transverse movement between said supports including a second

5 motor, means for effecting incremental movement of said motor including a valve actuated by said pilot valve, and means for determining the magnitude of said increments including a throttle valve for controlling the volume of fluid supplied to said second motor.

15. In a grinding machine, a work support, a grinding wheel support, mechanism for effecting a relative longitudinal movement of said supports, means for effecting a relative transverse movement between said supports including a feed screw, a motor for moving said screw bodily and axially to position said supports for a grinding operation, means for effecting said transverse movement at a slower rate during a grinding operation including a motor for rotating said screw, a reversing mechanism for said longitudinal movement, connections between said reversing mechanism and said slow feeding means for advancing said rotating motor intermittently in timed relation with the reversal of said longitudinal movement, and bypass means around said reversing mechanism for actuating said screw rotating motor continuously and automatically in the opposite direction in timed relation with said transverse positioning movement to separate said supports whereby to reset said slow feed means for the next grinding operation.

16. In a grinding machine, a work support, mechanism for effecting a longitudinal reciprocation of said support including a hydraulic motor, a reversing mechanism for controlling said longitudinal reciprocating movement, a grinding wheel support, mechanism for effecting 30 a slow transverse feeding movement of said support, means controlled by said reversing mechanism for supplying fluid under pressure to said feeding mechanism intermittently, means for supplying a continuous flow of fluid under pressure to said feed mechanism, a valve controlled by said reversible mechanism and operable in one position to connect said hydraulic motor with said reversing mechanism and for connecting said feed mechanism with said intermittent flow 35 of fluid, and in another position to disconnect said hydraulic motor and said reversing mechanism and to connect said feed mechanism with said continuous flow of fluid under pressure, and means for operating said feed mechanism in the 40 opposite direction at a continuous rate for resetting same regardless of the position of said valve.
